CARRIAGE FOOTWELL

Nathan J. Kroll and Samuel Kroll, Chicago, Ill.

Application July 29, 1935, Serial No. 33,634

10 Claims. (Cl. 280—47)

This invention relates to a carriage footwell. It is an object of this invention to provide an improved carriage footwell which is relatively simple and inexpensive in construction and efficient in use.

Another object of the present invention is to provide a new and improved footwell or foot rest for a baby carriage, doll buggy, toy carriage or the like.

10 Other objects will appear hereinafter.

The invention consists in the novel combination and arrangement of parts to be hereinafter described and claimed.

The invention will best be understood by reference to the accompanying drawings, showing the preferred form of construction and in which:

Fig. 1 is a side elevational view of a baby carriage embodying a preferred form of the present invention;

20 Fig. 2 is a rear elevational view of the same, on line 2—2 in Fig. 1;

Fig. 3 is a bottom plan view, partly in section, on line 3—3 in Fig. 2, showing the mechanism for moving the footwell relative to the body of the carriage and for latching the same in raised position;

Fig. 4 is a sectional view, on line 4—4 in Fig. 3, showing the footwell in raised and rearwardly extended horizontal position;

30 Fig. 5 is a perspective detail view, showing the means, embodied in the present invention, by which the springs of the carriage are anchored to the supporting frame of the same;

Fig. 6 is a sectional view, on line 6—6 in Fig. 3;

35 Fig. 7 is a top plan view, partly in section, on line 7—7 in Fig. 6;

Fig. 8 is a top plan view, partly in section, on line 8—8 in Fig. 6;

Fig. 9 is a sectional view on line 9—9 in Fig. 40 3; and

Fig. 10 is a sectional view showing the foot rest or well in dropped or lowered position and in which position its acts as a foot rest for the occupant of the carriage.

45 A carriage embodying a preferred form of the present invention is shown in the drawings, is therein generally indicated at 15, and for the purpose of illustrating the present invention the same is shown as used in conjunction with a baby carriage which includes a body 16, a wheel-bearing supporting frame 17, front and rear wheels 18 and 19, respectively, which are carried by the said supporting frame 17, and a handle or operating member which is generally indicated at 41 and which includes a horizontally extending

handle bar 42. The handle or operating member 41 includes depending arms 43 and these arms 43 include end portions 45 which are attached, as at 55, to horizontal extensions or relatively narrow strips 59 which are formed as part of the bottom wall or flooring 26 of the body 16 (Fig. 6).

Mounted on each of the extensions 59 of the bottom wall 26 of the body 16 of the carriage 15 and attached thereto, as at 52 (Fig. 6), are 10 vertically spaced horizontally extending rails 44 which provide trackways 25 (Figs. 3, 5, and 8).

The present invention is particularly concerned with the provision of a new and improved foot rest or footwell for a baby carriage, doll buggy, 15 toy carriage or the like, and such a foot rest or well is generally indicated at 20 in the drawings, and is arranged at one end of the body 16 of the carriage 15, and preferably at the rear end of the same.

20 The foot rest or well 20 comprises an end or rear wall 21, a base or bottom wall 22, and side walls 23. Mounted on the bottom wall 22 of the footwell 20 is a horizontally extending rod 24 and this rod 24 has end portions 39 which project between the top and bottom walls 44 of the trackways 25 so as to be slidable therein (Figs. 3 and 8).

25 Inward movement of the foot rest or well 20, (right to left, Fig. 3), relative to the body 16 of the carriage 15, is limited by engagement of the end portions 39 of the rod 24 with stops 40 (Figs. 3 and 8) which are mounted in the trackways 25.

30 Pivottally mounted between its ends, as at 27, (Fig. 3) upon the bottom wall 22 of the foot rest or well 20 is a lever 28 which includes a handle portion 29 and this handle portion 29 projects rearwardly of the foot rest or well 20 so that it may readily be grasped by the operator of the carriage; and attached to the lever 28 is a 40 coil spring 30 which urges the lever 28—29 into its normal or initial position (as in full lines, Fig. 3).

35 Pivottally connected to the lever 28, between the ends of the latter, as at 31 (Fig. 3), is a latch rod 32 which is slidably mounted upon the bottom wall 22 of the foot rest or well 20 (Fig. 3), and pivottally connected to the lever 28 at one end of the latter, as at 33, is a latch rod 34 which is likewise slidably mounted upon the bottom wall 22 of the foot rest or well 20 (Fig. 3).

45 The latch rod 32 has an end portion 35 (Figs. 3 and 9) which is slidably mounted in the corresponding trackway 25 (Figs. 3 and 9), and this end portion 35 of the latch rod 32 is latchingly 50

55

engageable in a socket or recess 36 which is formed in a flat metal re-inforcing bar or plate 54 (Figs. 6 and 8); there being one of these bars or plates 54 between the horizontally extending rails 44 of each of the trackways 25; and similarly, the latch rod 34 is slidably mounted in the other trackway 25 and has an end portion 37 which is latchingly engageable in a socket or recess 38 which is formed in the corresponding plate or bar 54 (Fig. 8).

Formed in the lower or bottom rails 44 of the trackways 25 (Figs. 3 and 8), in alignment with the end portions 35 and 37 of the latch rods 32 and 34, respectively, are openings or slots 60.

Attached to the flat metal reinforcing bar or plate 54 and at opposite sides of the carriage 15 (Fig. 4), are depending guideways or trackways 46 and the end portions 35 and 37 of the latch rods 32 and 34, respectively, are engageable in

these trackways or guideways 46. Formed in each of these guideways 46, adjacent the lower end of the same (Fig. 4) is a latch opening 58 and the end portions 35 and 37 of the latch rods 32 and 34, respectively, are latchingly engageable in these openings 58 so as to hold the foot well 20 in lowered position (as in Fig. 10), as will be explained more fully hereinafter.

Provided in each of the metal plates 54 (Fig. 5) is a transversely extending slot or groove 48, (Fig. 30 5), and mounted in each of these grooves 48 is an arm or bar 49. Extended into a suitable opening provided therefor in each of the bars 49 is a truss bolt 47 (Fig. 9). Each of these truss bolts 47 supports a yoke 50, and the end portions of the springs 51 of the carriage are attached to the supporting frame 11 of the carriage by means of these yokes 50.

A strip of elastic fabric or other flexible elastic material 53 (Figs. 4, 7, and 10) is inserted between the inner end of the footwell 20 and the bottom wall 26 of the body 16 of the carriage, this elastic fabric strip 53 having one end attached to the foot well 20 and having its other end attached to the bottom wall 26 of the body 45 16 of the carriage 15.

Provided in each of the metal bars 54 adjacent the rear or outer end of the same (right hand end, as seen in Fig. 8), is a recess or socket 56 and mounted in each of the trackways 25 adjacent the corresponding socket or recess 56 is a stop 57.

Operation

The extensible and adjustable footwell or foot rest 20 is normally latched in raised and inwardly extended position (as in full lines, position "A", Fig. 1) by means of the end portions 35 and 37 of the latch rods 32 and 34, respectively, which are normally urged, by the spring 30, into latching engagement with the sockets or recesses 36 and 38, respectively, which are formed in the rails 54.

However, if the operator of the vehicle desires to extend the foot rest or well 20 so as to provide, in effect, a horizontal extension or elongation of the bottom wall 26 of the body 16 of the carriage 15, this may be accomplished by moving the hand lever 28-29 (counterclockwise, from full to dotted line position, Fig. 3), against the action of the spring 30, thereby withdrawing the end portions 35 and 37 of the latch rods 32 and 34, respectively, out of latching engagement with the sockets or recesses 36 and 38, respectively, which are formed in the rails or bars 54, whereupon the 75 foot rest or well 20 may be drawn rearwardly

into the position in which it is shown in Fig. 4, position "B", Fig. 1) by means of the handle portion 29 of the lever 28, it being noted that during this movement of the footwell 20, relative to the body 16 of the carriage 15, the end portions 29, 5 25 and 37 of the rods 24, 32, and 34, respectively, ride upon the bottom rails 44 of the trackways 25.

When the footwell 20 reaches its rearwardly extended horizontal position (as in Fig. 4, position "B", Fig. 1), the operator releases the handle or lever 28-29, whereupon the tensioned spring 30 urges the lever 28-29 back into its initial position (counterclockwise, from full to dotted line position, Fig. 1), thereby projecting the end portions 35 and 37 of the latch rods 32 and 34, respectively, 15 into the sockets 56 which are formed in the metal rails or bars 54 (Fig. 8), and thus latching the footwell 20 in its rearwardly extended horizontal position (as in Fig. 4, position "B", Fig. 1), and in which position the footwell 20 provides, in effect, a horizontal extension of the bottom wall 26 of the body 16 of the carriage 15 so that the occupant of the carriage may lie therein in a reclining position; it being noted this rearward movement of the footwell 20, relative to the body 20 16 of the carriage 15, (left to right, Figs. 1 and 4) is limited by the engagement of the end portions 35 and 37 of the latch rods 32 and 34, respectively, 25 with the stops 57 which are arranged in the trackways 25 (Fig. 8).

To return the footwell from its rearwardly extended horizontal position (as in Fig. 4, position "B", Fig. 1), the lever 28-29 may be operated (from full to dotted line position, Fig. 3), so as to withdraw the end portions 35 and 37 of the latch rods 32 and 34, respectively, out of the sockets 56, whereupon the tensioned elastic web 53 will return the footwell 20 back into its initial position (as in full lines, position "A", Fig. 1), it being noted that during this movement of the 40 footwell 20 the end portions 39, 35, and 37 of the rods 24, 32, and 34, respectively, ride upon the bottom rails 44 of the trackways 25.

When the footwell 20 reaches its initial position, (position "A", Fig. 1), the tensioned spring 45 30 will again urge the end portions 35 and 37 of the latch rods 32 and 34, respectively, back into the sockets 36 and 38, respectively, thereby latching the footwell 20 in its normal and initial position (as in full lines, position "A", Fig. 1). 50

However, if the operator of the vehicle desires to drop the footwell or rest 20 into lowered position (position "C", Fig. 1, or into the position in which it is shown in Fig. 10) this may be accomplished by manipulating the latch handle 28-29, 55 from full to dotted line position, Fig. 3, so as to withdraw the end portions 35 and 37 of the latch rods 32 and 34, respectively, out of their sockets 36 and 38, respectively, and then pivoting the footwell 20 downwardly, whereupon the end portions 35 and 37 of the latch rods 32 and 34, respectively, will pass through the slots or openings 60 which are formed in the bottom rails 44 of the trackways 25 (Fig. 8), the footwell 20 being pivoted downwardly manually, by means of the 65 handle or lever 28-29, until the end portions 35 and 37 of the latch rods 32 and 34, respectively, come into alignment or registration with the latch openings 58 in the guideways or trackways 46 (Fig. 4), whereupon the tensioned spring 30 will 70 urge the latch rods 32 and 34 apart so as to project their end portions 35 and 37, respectively, into the latch openings 58 (Fig. 4), thereby latching the footwell 20 in the position in which it is shown in Fig. 10, (position "C", Fig. 1). 75

It is to be noted that the end portions 39 of the horizontally extending rod 24 are normally disposed in engagement with the stops 40 provided in the trackways 25, and that this position forms a pivot when the footwell 20 is lowered into position (Fig. 1).

When in lowered position, as in Fig. 10, the footwell 20 provides a convenient foot rest for the occupant of the carriage, when the said occupant is disposed therein in an upright position.

To return the footwell 20 from its lowered position, as in Fig. 10, back into its normal or initial position, (as in full lines, position "A", Fig. 1), the operator grasps the handle or lever 28—29 and pivots the same (counterclockwise, from full to dotted line position, Fig. 3), thereby withdrawing the end portions 35 and 37 of the latch rods 32 and 34, respectively, out of latching engagement with the latch openings 58 which are formed in the guideways 46 (Fig. 4), whereupon the tensioned elastic web 53 will pivot the footwell 20 upwardly (counterclockwise, Fig. 10) until the end portions 35 and 37 of the latch rods 32 and 34, respectively, enter the trackways 25, whereupon the tensioned spring 30 will urge the end portions 35 and 37 of the latch rods 32 and 34, respectively, into the sockets 36 and 38, respectively.

It is to be noted in connection with the present carriage that the flat metal rails or bars 54 perform several functions, that is, they reinforce the relatively narrow extensions or strips 59 of the bottom wall or flooring 26 of the body 16 of the carriage 15 (Fig. 9); they reinforce the trackways 25, between the rails 44 of which they are arranged; they provide a means for anchoring the truss bolts 41; they act as guides for the end portions 39 of the rod 24, as well as for the end portions 35 and 37 of the latch rods 32 and 34, respectively; and they co-operate with the rails 44 of the trackways 25, and with the end portions 39 of the rod 24, to provide pivots for the footwell 20 during the operation of moving the footwell 20 into and out of its dropped or lowered position (as in Fig. 10).

It is also to be noted that while the footwell 20 has been described as applied specifically to a baby carriage, and this is the purpose for which it is primarily intended, it may also be used in conjunction with doll buggies, toy carriages, and the like.

While we have illustrated and described the preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claims.

Having thus described our invention what we claim as new and desire to protect by Letters Patent is:

1. In a carriage of the character described, a wheel-bearing supporting frame, a body carried by the said supporting frame and including spaced, parallel, horizontally extending trackways each having a socket formed therein, each of said trackways including an upper rail and a bottom rail and each of the latter having an opening formed therein, a footwell arranged at one end of said body and including a bottom wall, a member mounted upon the said bottom wall of said footwell and including end portions extending into said trackways for pivotally mounting

the said footwell upon the said body, means for latching the said footwell in raised position upon said body including latch members slidably mounted upon the said footwell and having end portions receivable in said sockets, and a manually operable member for operating the said latch members so as to move the said end portions thereof out of said sockets and downwardly through said openings and thereby move the said footwell into lowered position.

2. In a carriage of the character described, a wheel-bearing supporting frame, a body carried by the said supporting frame and including spaced, parallel, horizontally extending trackways each having a socket formed therein, each of said trackways including an upper rail and a bottom rail and each of the latter having an opening formed therein, a footwell arranged at one end of said body and including a bottom wall, a member mounted on the bottom wall of said footwell and including end portions extending into said trackways for pivotally mounting the said footwell upon the said body, and means for latching the said footwell in raised position upon the said body including latch members slidably mounted upon the said footwell and having end portions receivable in said sockets, means normally urging the said latch members in a direction to move the said end portions thereof into said sockets, and a manually operable member for operating the said latch members so as to move the said end portions thereof out of said sockets, against the action of said urging means, and downwardly through said openings so as to move the said footwell into lowered position.

3. In a carriage of the character described, a wheel-bearing supporting frame, a body carried by the said supporting frame and including spaced, parallel, horizontally extending trackways each having a socket formed therein, each of said trackways including an upper rail and a bottom rail and each of the latter having an opening formed therein, a footwell arranged at one end of said body and including a bottom wall, a member mounted on the bottom wall of said footwell and including end portions extending into said trackways for pivotally mounting the said footwell upon the said body, and means for latching the said footwell in raised position upon the said body including latch members slidably mounted upon the said footwell and having end portions receivable in said sockets, a manually operable member for operating the said latch members so as to move the said end portions thereof out of said sockets and downwardly through said openings and thereby move the said footwell into lowered position, and a flexible elastic member having one end portion attached to the said body and having its other end portion attached to the said footwell for raising the latter from lowered position into upright or horizontal position.

4. In a carriage of the character described, a wheel-bearing supporting frame, a body carried by the said supporting frame and including spaced, parallel, horizontally extending trackways each having a socket formed therein, each of said trackways including an upper rail and a bottom rail and each of the latter having an opening formed therein, a footwell arranged at one end of said body and including a bottom wall, a member mounted on the bottom wall of said footwell and including end portions extending into said trackways for pivotally mounting the said footwell upon the said body, means

for latching the said footwell in raised position upon said body including latch members slidably mounted upon the said footwell and having end portions extending into said sockets, and a manually operable member for operating the said latch members so as to move the said end portions thereof out of said sockets and downwardly through said openings and thereby move the said footwell into lowered position, means coacting with the said latch members for latching the said footwell in lowered position, and means for automatically returning the footwell from lowered position to raised or horizontal position if and when the said latch members are moved out of latching engagement with the said second-named means.

5. In a carriage of the character described, a wheel-bearing supporting frame, a body carried by the said supporting frame and including spaced, parallel, horizontally extending trackways each having a socket formed therein, each of said trackways including an upper rail and a bottom rail and each of the latter having an opening formed therein, a footwell arranged at one end of said body and including a bottom wall, a member mounted on the bottom wall of said footwell and including end portions extending into said trackways for pivotally mounting the said footwell upon the said body, means for latching the said footwell in raised position upon the said body including latch members slidably mounted upon the said footwell and having end portions extending into said sockets, a manually operable member for operating the said latch members so as to move the said end portions thereof out of said sockets and downwardly through said openings and thereby move the said footwell into lowered position, and a guide member carried by the said body at each side thereof and depending therebelow, each of said guide members having a latch opening formed therein, and the said latch members being receivable in said second-named openings for latching said footwell in lowered position.

45. 6. In a carriage of the character described, a wheel-bearing supporting frame, a body carried by the said supporting frame and including spaced, parallel, horizontally extending trackways each having a socket formed therein, each of said trackways including an upper rail and a bottom rail and each of the latter having an opening formed therein, a footwell arranged at one end of said body and including a bottom wall, a member mounted on the bottom wall of said footwell and including end portions extending into said trackways for pivotally mounting the said footwell upon the said body, means for latching the said footwell in raised position upon the said body including latch members slidably mounted upon the said footwell and having end portions receivable in said sockets, means normally urging the said latch members in a direction to move the said end portions thereof into said sockets, a manually operable member for operating the said latch members so as to move the said end portions thereof out of said sockets, against the action of said urging means, and downwardly through said openings and thereby move the said footwell into lowered position, and a guide member carried by the said body at each side thereof and depending therebelow, each of said guide members having a latch opening formed therein, and said latch members being urged by said urging means into said second-named openings, when the said footwell is in

lowered position, so as to latch the said footwell in lowered position.

7. In a carriage of the character described, a wheel-bearing supporting frame, a body carried by the said supporting frame and including spaced, parallel, horizontally extending trackways each having a socket formed therein, each of said trackways including an upper rail and a bottom rail and each of the latter having an opening formed therein, a footwell arranged at one end of said body and including a bottom wall, a member mounted on the bottom wall of said footwell and including end portions extending into said trackways for pivotally mounting the said footwell upon the said body, means for latching the said footwell in raised position upon the said body including latch members slidably mounted upon the said footwell and having end portions extending into said sockets, means normally urging the said latch members in a direction to move the said end portions thereof into said sockets, a manually operable member for operating the said latch member so as to move the said end portions thereof out of said sockets, against the action of said urging means, and downwardly through said openings and thereby move the said footwell into lowered position, a guide member carried by the said body at each side thereof and depending therebelow, each of said guide members having a latch opening formed therein, and said latch members being urged by said urging means into said second-named openings, when the said footwell is in lowered position, so as to latch the said footwell in lowered position, and means for automatically raising the said footwell into raised position if and when the said latch members are moved out of latching engagement with said second-named openings against the action of said urging means.

8. In a carriage of the character described, a wheel-bearing supporting frame, a body carried by the said supporting frame and including spaced, parallel, horizontally extending trackways each having a socket formed therein, each of said trackways including an upper rail and a bottom rail and each of the latter having an opening formed therein, a footwell arranged at one end of said body and including a bottom wall, a member mounted on the bottom wall of said footwell and including end portions extending into said trackways for pivotally mounting the said footwell upon the said body, means for latching the said footwell in raised position upon said body including latch rods slidably mounted upon the said footwell and having end portions receivable in said sockets, means normally urging the said latch members in a direction to move the said end portions thereof into said sockets, a manually operable member for operating the said latch members so as to move the said end portions thereof out of said sockets, against the action of said urging means, and downwardly through said openings and thereby move the said footwell into lowered position, a guide member carried by the said body at each side thereof and depending therebelow, each of said guide members having a latch opening formed therein, and said latch members being urged by said urging means into said second-named openings, when the said footwell is in lowered position, so as to latch said footwell in lowered position, and a flexible elastic member having an end portion attached to the said footwell and having an end portion attached to the said body for automatically raising the said footwell into raised posi-

tion if and when the said latch members are moved out of latching engagement with the said second-named openings against the action of said urging means.

5. 9. In a carriage of the character described, a wheel-bearing supporting frame, a body carried by the said supporting frame and including spaced horizontally extending trackways, springs for yieldably supporting the said body upon said frame, a footwell at one end of said body and including a bottom wall, each of said trackways including a pair of vertically spaced horizontally extending rails, each of said trackways also including a reenforcing member arranged between the said rails of the same, each of said reenforcing members having a slot formed therein and extending transversely thereof, and means for attaching the said springs to the said body including a member arranged in each of said slots.
10. 10. In a carriage of the character described, a wheel-bearing supporting frame, a body carried by the said supporting frame and including spaced horizontally extending trackways, springs for yieldably supporting the said body upon said frame, a footwell at one end of said body and including a bottom wall, each of said trackways including a pair of vertically spaced horizontally extending rails, each of said trackways also including a reenforcing member arranged between the said rails of the same, each of said reenforcing members having a slot formed therein and extending transversely thereof, means for attaching the said springs to the said body including a member arranged in each of said slots, said last-named means also including a truss bolt attached to each of said last-named members for supporting the corresponding one of said springs.

SAMUEL KROLL
NATHAN J. KROLL. 20
